UNITED STATES PATENT OFFICE.

HANS REALF OTTESEN, OF HANOVER, GERMANY.

ELECTRIC-ARC LAMP.

SPECIFICATION forming part of Letters Patent No. 626,717, dated June 13, 1899.

Application filed January 5, 1899. Serial No. 701,253. (No model.)

To all whom it may concern:

Be it known that I, HANS REALF OTTESEN, engineer, a subject of the King of Sweden and Norway, and a resident of the city of Hanover, in the Kingdom of Prussia, German Empire, have invented certain new and useful Improvements in Arc-Lamps, of which the following is a specification.

The objects of my invention are arc-lamps in which the carbons, owing to the way in which they are suspended, form a voltaic arc which remains of constant length and always occupies the same position quite independently of the combustion of the carbons. In the invention an insulating-plate is introduced between the ends of the carbons, giving an intense illuminating effect when raised to white heat.

Referring to the drawings which form a part of this specification, Figure 1 shows the mathematical principle on which the invention is based. Fig. 2 represents the improved arc-lamp in front elevation, and Fig. 3 represents the same in side elevation, and Fig. 4 represents a part in detail.

With points A, B, and C, Fig. 1, as centers three segments of circles whose radii are respectively r , r' , and r' are drawn intersecting each other at the point F, so that from every straight line drawn from the point F equal lengths p are cut off between the two circles whose centers are A and B on one side and those whose centers are A and C on the other—thus, for instance, $D'E'=D^2E^2=D^3E^3$, and so on. If now the radii r and r' represent rods pivoted at A, B, and C and connected by pivots at their outer extremities to a third, as will be hereinafter more fully described, equal to p in length, then whatever may be the position occupied by r and r' p will always occupy such a position that its elongation passes through F. This fact has been utilized by me in my improved arc-lamp.

The two carbons a , a , Fig. 2, are not arranged vertically one over the other, but are both slightly inclined relatively to the horizon, so as to form an obtuse angle with one another. They are secured in the carbon-holders c , c (shown in detail in Fig. 4) by means of screws b , b .

Rods f and g are pivoted to the carbon-holders by the pins d and e and are adapted

to turn on the pivots h and i , suitably fixed in the face-plates k , k . The distance between the centers of the joints d and e corresponds with the constant length p in Fig. 1. The rods g are provided with lateral arms l , on which weights m can be placed. The arms f and g are of insulating material or are insulated by insulating-pieces from the holders. 60

Between the two carbon rods, which are pressed toward each other by the weights m and which always meet in the focus n , passes the separating-piece q , fixed to the rod o . This piece consists of an incombustible non-conducting substance, such as kaolin, porcelain, or the like. The voltaic arc now passes in a curve around the bottom of the plate q , and since this plate is of a constant thickness the arc is likewise always of the same length. The thickness of the plate q is chosen in accordance with the tension employed, and thus arcs varying in length may be obtained.

The current may pass through the magnets and the carbons in series.

The rod o is connected to the armature t of the magnets u . Weights w , capable of adjustment upon the arms v , connected with the armature t , tend to lift the armature t , and consequently also the plate q . When the current through the magnets is switched off, the plate is drawn away from between the two carbons and the latter come into contact. When the current is switched on again, the armature t is pulled downward, the carbons are forced apart by the plate q , and the arc is struck.

The whole lamp is suspended from the bolt s , which passes through the face-plates k , k .

If the lamp is not to be used as a suspended lamp, but in any other position—for instance, in connection with a reflector—springs must be substituted for the weights m and w .

My improved lamp may be equally well employed for continuous or for alternating currents.

My improved lamp presents certain advantages, inasmuch as by my method of suspending the carbons the regulating mechanism is dispensed with, while nevertheless the length of the arc remains practically constant and is not subject to displacement in space. Moreover, a very favorable illuminating effect is obtained, seeing that the insulating-plate is

raised to a white heat and emits an intense light, similar to lime-light.

Having now described my invention, what I claim as new, and desire to secure by Letters 5 Patent, is—

1. In an arc-lamp, the combination, with the frame, of a pair of carbon-holders arranged inclining toward each other, a pair of links connecting each carbon-holder with the
- 10 lamp-frame, a separating-plate of insulating material and means for holding the same between the ends of the carbons, substantially as described.
- 15 2. In an arc-lamp, the combination with the lamp-frame of the carbon-holders, a pair

of links hinged to each carbon-holder and to the frame, said links holding each carbon-holder in a position inclined toward the other, weights for causing the carbon-holders and carbons to approach each other, an insulating-plate, a carrier therefor arranged to lower said plate between the points, and an electromagnet for raising and lowering said carrier, substantially as described. 20

In witness whereof I have hereunto set my 25 hand in presence of two witnesses.

HANS REALF OTTESEN.
